Primary Examiner — Abraham Bahta(74) Attorney, Agent, or Firm — Johnson | Dalal; Mark C. Johnson(57) CLAIM

The ornamental design for a prayer stool as shown and described.

DESCRIPTION

FIG. 1 is an elevational view of a prayer stool in accordance with the present invention;

FIG. 2 is a left-side view thereof;

FIG. 3 is a right-side view thereof;

FIG. 4 is a top plan view thereof;

FIG. 5 is a bottom plan view thereof;

FIG. 6 is a rear view thereof; and,

FIG. 7 is a perspective view thereof.

The broken lines shown in the drawings depict portions of the prayer stool in which the design is associated and are not considered part of the claimed design.
